UNITED STATES PATENT OFFICE.

WILLARD A. SPEAKMAN, OF WILMINGTON, DELAWARE.

LAVATORY-FITTING.

1,117,715.

Specification of Letters Patent.

Patented Nov. 17, 1914.

Application filed May 7, 1914. Serial No. 836,860.

To all whom it may concern:

Be it known that I, WILLARD A. SPEAKMAN, a citizen of the United States of America, residing in Wilmington, in the county of New Castle and State of Delaware, have invented certain new and useful Improvements in Lavatory-Fittings, of which the following is a true and exact description, reference being had to the accompanying drawings, which form a part thereof.

My present invention consists in an improved fitting especially devised and adapted to be inserted in an aperture in a lavatory basin slab, and formed with a passage adapted to receive a tubular waste valve, and with a mixing chamber for hot and cold water and with a delivery spout opening therefrom above the basin slab when the fitting is in place, and having provisions by which hot and cold water supply pipes may be secured to the fitting in communication with said mixing chamber beneath the basin slab.

25 The object of my invention, considered in one of its aspects, is to provide a simple and compact fitting of the character specified above, which is adapted to be inserted in a basin slab orifice not greatly exceeding in diameter the diameter of the tubular waste valve passage provided in the fitting.

More specifically, the object of my invention is to provide a satisfactory one-piece fitting of the general character specified, 35 having a waste valve passage adapted to receive a tubular waste valve of the usual size, while the fitting as a whole is of such size and form that it may be inserted in the central aperture of a standard form of basin slab having three apertures of the size, shape and arrangement commonly employed with separate hot and cold water supply valves mounted in the side apertures and each provided with an independent discharge spout 40 located above the basin slab, and with the central aperture receiving a fitting, the sole purpose of which is to provide a suitable housing for a tubular waste valve. My improved combination mixing nozzle and waste 45 valve fitting thus permits a standard basin slab to be fitted without any change in the slab structure with two different types of fittings, and thereby permits plumbers and plumbing supply houses to reduce the 50 amount of stock kept on hand without cor-

respondingly diminishing the different styles of apparatus.

The various features of novelty characterizing my invention are pointed out with particularity in the claims annexed to and forming a part of this specification. For a better understanding of the invention, however, and of the advantages possessed by it, reference should be had to the accompanying drawings and descriptive matter in which I have illustrated and described a preferred form in which my invention may be embodied.

Of the drawings: Figure 1 is a plan of a basin slab equipped with my improved fittings; Fig. 2 is an elevation, partly in section, on the line 2—2 of Fig. 1; Fig. 3 is a partial section on the line 3—3 of Fig. 5; Fig. 4 is a sectional plan taken on the line 4—4 of Fig. 3; and Fig. 5 is a section taken on the line 5—5 of Fig. 2.

In the drawings, A represents the slab and A' the bowl of a lavatory basin fixture of common form. This slab is formed with a central aperture A³ and two side apertures. 80 The cold water supply valve E is mounted in one, and the hot water supply valve E' is mounted in the other side aperture. These valves do not have discharge spouts above the basin slab; but, on the contrary, have their discharge pipes D connected to the mixing chamber B' of the central fitting B, which passes through the central slab aperture A³.

The central fitting B, as shown, is formed with a head portion B² above the slab, and 90 larger in diameter than the aperture A³, and engaging the upper surface of the slab at the margin of the aperture A³. The body portion of the fitting B immediately beneath the head B² is cylindrical and is externally 95 threaded to receive the nut C by which the fitting is clamped in place. The mixing chamber B' is shaped with a view of insuring a mixing chamber of ample size along side of the passage B³ provided for a tubular waste valve F of the usual form and size. As shown the mixing chamber B' is arc-shaped in horizontal cross section. A delivery spout B⁴ projecting from the head B² passes water from the mixing chamber 105 B' to the basin bowl A'. Beneath the slab A the fitting B is formed with threaded bosses B⁵ to which the ends of the pipes D are connected. Advantageously, as shown, the threaded bosses B⁵ have their centers 110

well to the rear of the center line of the waste valve passage B⁴, as this facilitates the connection of the pipes D thereto. The fitting B is a one piece structure, preferably 5 in the form of an integral casting.

As shown, the wall surrounding the passage B³ is internally threaded at its lower end to receive the upper end of a tubular part G which is connected to a casing H. 10 The latter is connected at its side to the outlet orifice A² in the bottom of the basin bowl by the pipe I. At its lower end the casing H is connected to the waste pipe J by a port surrounded at its upper end by the seat H' 15 for the waste valve F. The internal diameter of casing H and of the tubular part G is appreciably greater than the external diameter of the waste valve F to permit the water to pass from the bowl A' to the over- 20 flow ports F' in the hollow valve F when the maximum height of water level in the bowl is reached. The body of the fitting B is reduced in diameter between its threaded upper end portion and its lower end, and 25 the corresponding portion of the mixing chamber B' may be regarded as located in a hollow rib-like projection from the outer wall of this cylindrical guide.

It will be apparent to those skilled in the 30 art that the construction disclosed herein is exceedingly simple and effective. The lower end of the fitting B may be readily threaded through a basin slab orifice A³ of the usual size and shape provided for a 35 plain tubular waste valve fitting, while at the same time the passage B³ is adapted to receive a waste valve F of the usual size, and the mixing chamber B' is of ample cross section. The reduction in diameter of 40 the body portion of the fitting B between its ends facilitates the passage of the enlarged lower end of the fitting through the orifice A³ and the passage of the clamping nut C onto the body portion of the fitting.

Having now described my invention, what 45 I claim as new and desire to secure by Letters Patent, is:

1. A combination one-piece mixing nozzle

and waste valve fitting comprising a tubular body enlarged at one end to form a head 50 adapted to seat against a support at the margin of an aperture in the latter receiving said tubular body and having a delivery spout projecting from said head at one side, said tubular body comprising a cylindrical 55 portion adjacent said head externally threaded to receive a clamping nut, said fitting being formed with a waste valve passage extending through said head and body and with a mixing chamber arc-shaped in 60 cross section and partially surrounding said passage, said mixing chamber communicating at its upper end with said delivery spout and said tubular body being formed adjacent its end remote from said head with 65 provisions for securing two supply pipes thereto in communication with said mixing chamber.

2. A combination one-piece mixing nozzle and waste valve fitting comprising a tubular body enlarged at one end to form a head 70 adapted to seat against a support at the margin of an aperture in the latter receiving said tubular body and having a delivery spout projecting from said head at one side, said tubular body comprising a cylindrical 75 portion adjacent said head externally threaded to receive a clamping nut, said fitting being formed with a waste valve passage extending through said head and body 80 and with a mixing chamber arc-shaped in cross section and partially surrounding said passage, said mixing chamber communicating at its upper end with said delivery spout and said tubular body being formed adjacent its end remote from said head with 85 two hollow arms through which two supply pipes may be placed in communication with said mixing chamber and being reduced in diameter between said threaded portion and 90 said arms.

WILLARD A. SPEAKMAN.
